US00D553234S

(12) **United States Design Patent** (10) Patent No.: **US D553,234 S**
Herbst et al. (45) Date of Patent: **** Oct. 16, 2007**

(54) **CEILING EXHAUST FAN**

(75) Inventors: **Walter Herbst**, Lake Forest, IL (US);
John D. Hartman, Chicago, IL (US)

(73) Assignee: **J. F. Meskill Enterprises, LLC**,
Cleveland, OH (US)

(**) Term: **14 Years**

(21) Appl. No.: **29/228,156**

(22) Filed: **Apr. 20, 2005**

(51) LOC (8) Cl. **23-04**

(52) U.S. Cl. **D23/372**

(58) Field of Classification Search **D23/372**,
D23/371, 385; 454/349, 354

See application file for complete search history.

(57) **CLAIM**

The ornamental design for a ceiling exhaust fan, as shown and described.

DESCRIPTION

FIG. 1 is a top plan view of a ceiling exhaust fan;

FIG. 2 is a front plan view thereof;

FIG. 3 is a first side plan view thereof;

FIG. 4 is a second side plan view thereof; and,

FIG. 5 is a rear plan view thereof.

The broken line showing of the concentric circular members is included for the purpose of illustrating environmental structure and forms no part of the claimed design.
